UNITED STATES PATENT OFFICE.

BENJAMIN SILVERMAN, OF CHATTANOOGA, TENNESSEE, ASSIGNOR OF ONE-HALF TO
J. RUSSEL EARP, OF CHATTANOOGA, TENNESSEE.

COMB.

Application filed July 23, 1924. Serial No. 727,644.

To all whom it may concern:

Be it known that BENJAMIN SILVERMAN, a citizen of the United States, residing at Chattanooga, in the county of Hamilton and State of Tennessee, has invented certain new and useful Improvements in Combs, of which the following is a specification.

This invention relates to metal combs for use in straightening wavy or kinky hair and has special reference to a comb having a tooth or head portion reversible on the handle.

One important object of the invention is to provide a novel construction in a comb of this description where the comb will be supported throughout its length on a handle shank.

A second important object of the invention is to provide an improved construction so that the handle shank may be introduced from either end of the comb and there secured.

A third important object of the invention is to provide an improved handle assembly for combs of this description.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a side elevation of a comb constructed in accordance with this invention, the comb head being shown in section to disclose the handle shank arrangement.

Figure 2 is a detail view partly in section showing the handle assembly.

Figure 3 is a detail section of the hollow assembling tube used with the comb head and showing the arrangement by means of which the handle may be secured at either end.

Figure 4 is a section on the line 4—4 of Figure 1 with the comb head positioned on the handle as in that figure.

Figure 5 is a section similar to Figure 4, but with the comb head reversed.

In the construction of the invention herein disclosed it will be seen that there is provided a comb head having a hollow tube 10 extending from end to end and that on this hollow tube are assembled the teeth 11 and

spacers 12. The particular manner in which I prefer to accomplish this assembly is set forth in my companion application executed of even date herewith and bearing the serial number 727,643. At each end of the hollow tube 10 there is provided an internal threaded portion 13.

The handle consists of a shank member having a portion 14 of such size as to fit close in the tube 10 and at the handle end of this portion there is provided a threaded portion 15 of proper size and pitch to screw into the tube when inserted from either end. It is to be noted that the combined length of the portions 14 and 15 are equal to the 70 comb head and that the end 14 not only fits the metal part of the tube 10 but that the threads are so cut that they engage this portion 13 thus, when the head is in position on the shank it is supported from end to end. The handle end of the shank is indicated at 16 and on this handle end is assembled a thimble 17 which bears against the screw 75 threaded portion 15 and a wood or other insulating grip 18 which is held in position 80 on the shank portion 16 by means of a nut 19 screwed on the threaded end 20, this portion projecting through the grip for this purpose.

It will now be seen that the head may be applied to the handle with either end next the grip and that where the comb teeth are curved, as shown in Figures 4 and 5, the device may be arranged for either right hand or left hand movement.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come 100 within the scope claimed.

Having thus described the invention, what is claimed as new is:

1. In a device of the kind described, a comb head comprising a cylindrical tube 105 having an internally threaded portion at each end and a handle provided with a threaded shank selectively engageable in the threaded ends of said tube.
2. In a device of the kind described, a 110

- comb head comprising a cylindrical tube having an internally threaded portion at each end, and a handle shank provided with a threaded portion selectively engageable in the threaded ends of the tube, said shank having a tang portion extending from the threaded portion in axial alinement therewith and a grip mounted on said tang portion.
- 10 3. In a device of the kind described, a comb head comprising a cylindrical tube internally threaded portion at each end, a handle shank provided with a threaded por-

tion selectively engageable in the threaded ends of the tube, said shank further having a 15 tang portion extending from the threaded portion in axial alinement therewith, a thimble mounted on said tang portion and bearing against the threaded portion to form a stop at the handle end thereof, a heat 20 insulating grip mounted on the tang portion and bearing against said thimble and means for removably securing the grip in position.

In testimony whereof I affix my signature.
BENJAMIN SILVERMAN.
